JACKET WITH BISWING GUSSET IN FRONT
AND IN BACKCharles E. Enck, Ashland, Ohio, assignor to
Cresco Manufacturing Company, Ashland,
Ohio, a corporation of Ohio

Application December 31, 1947, Serial No. 795,099

7 Claims. (Cl. 2—93)

1

This invention relates to an article of wearing apparel, and particularly to coats, jackets or other outer garments. However, the invention is not to be restricted to outer garments only because it can be used on any garment that has a sleeve.

It is well known that in garments having long sleeves there is considerable binding across the shoulders of the person wearing the garment when the arm is moved to and fro. It is therefore the purpose of this invention to provide a sleeve attachment to a garment by which complete freedom of arm movement can be obtained without binding of the garment across the shoulders of the person wearing the same or across the breast of the person.

It has been a feature, particularly in men's clothing, of placing a bi-swing at each side of the back panel of a coat or jacket between the panel and the sleeve so that forward arm movement would not be restricted. However, no attention has been given to a removal of the restriction to the front part of the garment, it being considered that a normally open coat or jacket would be sufficiently free from restriction.

However, with the advent of articles of clothing, such as sport jackets and many other kinds of outer garments having full-length zippers extending from the collar of the garment to its lower extremity, considerable restriction has been occasioned across the front of the garment by rearward arm movement of the person wearing the garment.

It is therefore an object of this invention to provide an article of apparel with complete freedom of sleeve movement to eliminate binding across either the back or the front of the garment when the arm of the wearer is moved to and fro.

In this invention this is accomplished by placing a bi-swing between the back panel and the sleeve of the garment and between the front panel and the sleeve of the garment.

It is still a further object of the invention to provide a bi-swing construction for the front and back of a garment in which the bi-swing automatically restricts itself into a parallel position along the back or front panel respectively of the garment when the arm of the wearer of the garment is in a normal hanging position.

It is still another object of the invention to provide a front bi-swing and a back bi-swing for a garment that is relatively indistinguishable when the arm of the wearer of the garment is in a normal hanging position.

It is another object of the invention to provide a front bi-swing and a back bi-swing for a gar-

2

ment that extends from the shoulder seam of the garment to beneath the under-arm portion of the sleeve, and thereby provide complete freedom of sleeve movement.

It is still another object of the invention to provide a front bi-swing and a back bi-swing for a garment, each of which is constructed from two separate panels that are stitched together along one edge to insure that the panels will always fold into parallel relationship when the sleeve of the garment is in a normal hanging position.

Further objects and advantages will become apparent from the drawings and the following description.

In the drawings:

Figure 1 is a front elevational view of a jacket incorporating the invention showing the left sleeve of the jacket extended to illustrate the front bi-swing and with the right sleeve in a normal hanging position to illustrate the inconspicuousness of the front bi-swing.

Figure 2 is a rear elevational view of the jacket with the left sleeve extended for the same purpose as that of Figure 1.

Figure 3 is a side elevational view of the jacket but with the sleeve in cross-section.

Figure 4 is a horizontal cross-sectional view through the jacket taken along line 4—4 of Figure 1.

Figure 5 is a cross-sectional view taken along line 5—5 of Figure 1.

Figure 6 is a front elevational view showing the right bi-swing, but with the front panel broken away to more clearly illustrate the shape of the bi-swing panels.

Figure 7 is a rear elevational view showing the rear bi-swing but with the back panel broken away to more clearly illustrate the shape of the bi-swing panels.

Figure 8 is a top elevational view of a portion of the shoulder of the jacket but with the front and rear panels broken away to more clearly illustrate the connection of the bi-swing panels to the shoulder seam of the jacket.

Figure 9 is an enlarged cross-sectional view of a portion of the bi-swing illustrating the seam construction.

Figure 10 is an elevational view of the outer panel of the right front bi-swing.

Figure 11 is an elevational view of the inner panel of the right front bi-swing.

Figure 12 is an elevational view of the outer panel of the right back bi-swing.

Figure 13 is an elevational view of the inner panel of the right back bi-swing.

The invention is illustrated in use on a sport jacket 10. The jacket has a front panel 11 and a back panel 12, and is provided with a zippered front opening 13. The back panel 12 and the front panel 11 are connected together along the shoulder seam 14. The sleeves 15 and 16 of the jacket are of conventional construction.

A side gusset 46 is positioned between the front panel 11 and the rear panel 12, forming therewith a front side seam 17 and a rear side seam 18, the front and rear panels being connected to the gusset 46 along the seam lines 17 and 18.

The sleeve 15 is secured to the body of the jacket formed by the front and rear panels 11 and 12 at the shoulder seam, and is further directly connected to the body of the jacket by the side gusset 46 at the under-arm portion of the sleeve along the seam 19.

A front bi-swing 20 is placed between the front panel 11 and the sleeve 15. A back bi-swing 25 is placed between the back panel 12 and the sleeve 15.

The front bi-swing 20 consists of an outer panel 21 and an inner panel 22 that are laid in parallel relation and stitched together along the stitch-line 23.

The outer and inner panels 21 and 22 respectively have a common S-shaped configuration along the inner edge 24. The outer panel 21 is narrower than the inner panel 22 at the bottom portion thereof, shown in Figure 6, the left edge of the outer panel 21 being secured to the edge 26 of the arm opening in the front panel 11 along the stitch-line 27, thus securing the free end of the outer panel 21 of the right front bi-swing 20 to the outer panel 11.

The inner panel 22 has its free end 28 secured to the sleeve 15 along the seam-line 29.

The upper ends of the outer and inner panels 21 and 22 of the bi-swing 20 are secured in the shoulder seam 14, as shown in Figure 8.

The back right bi-swing 25 consists of the outer panel 31 and the inner panel 32 that are stitched together along their inner edges in the same manner as the front bi-swing 20.

The outer panel 31 is secured to the back panel 12 and the inner panel 32 is secured to the sleeve 15 in the same manner as the inner and outer panels for the front bi-swing 20.

The inner and outer panels 32 and 31 of the bi-swing 25 have a common S-shaped inner edge form 33, these panels being secured together along the stitch-line 34. The front edge of the outer panel 31 is secured to the back panel 12 along the stitch-line 35 while the front edge of the inner panel 32 is secured to the sleeve 15 along the seam-line 36.

With the front and back bi-swings 20 and 25 being constructed of independent panels secured together along one edge, which panels are in turn secured to the front and back panels of the jacket and to the sleeve of the jacket, there is provided a construction which insures correct folding of the bi-swings into position parallel with the front and back panels of the jacket whenever the sleeve of the jacket is in a normal hanging position.

While the construction of the article of apparel herein disclosed and described constitutes a preferred form, yet modifications of the construction are possible, and it is intended that such modifications that fall within the scope of the appended claims are intended to be included herein.

Having thus fully described my invention, what

I claim as new and desire to secure by Letters Patent is:

1. In an article of apparel such as a coat or the like, a front panel and a back panel connected along a shoulder seam and having a sleeve opening therebetween, a side gusset connecting said panels and forming therewith front and back side seams extending from the under-arm portion of the sleeve opening, a sleeve, said sleeve being connected to the front and back panels at the shoulder seam and to said gusset, and a front and back bi-swing extending from the shoulder seam to said front and back side seams respectively and connecting said sleeve to the edge of said sleeve opening in said front and back panels respectively.

2. In an article of apparel such as a coat or the like, a front panel and a back panel connected along a shoulder seam and having a sleeve opening therebetween, a side gusset connecting said panels and forming therewith front and back side seams extending from the under-arm portion of the sleeve opening, a sleeve, said sleeve being connected to the front and back panels at the shoulder seam and to said gusset, and a front and back bi-swing extending from the shoulder seam to said front and back side seams respectively and connecting said sleeve to the edge of said sleeve opening in said front and back panels respectively.

25 3. In an article of apparel such as a coat or the like, a front panel and a back panel connected along a shoulder seam and having a sleeve opening therebetween, a side gusset connecting said panels and forming therewith front and back side seams extending from the under-arm portion of the sleeve opening, a sleeve, said sleeve being connected to the front and back panels at the shoulder seam and to said gusset, and a front and back bi-swing extending from the shoulder seam to said front and back side seams respectively and connecting said sleeve to the edge of said sleeve opening in said front and back panels respectively, each of said bi-swings comprising an outer panel and an inner panel connected together along one edge thereof, said inner panel having its free edge connected to said sleeve and said outer panel having its free edge connected to said front and back panels respectively.

35 4. In an article of apparel such as a coat or the like, a front panel and a back panel connected along a shoulder seam and having a sleeve opening therebetween, a side gusset connecting said panels and forming therewith front and back side seams extending from the under-arm portion of the sleeve opening, a sleeve, said sleeve being connected to the front and back panels at the shoulder seam and to said gusset, and a front and back bi-swing extending from the shoulder seam to said front and back side seams respectively, each of said bi-swings comprising an outer panel and an inner panel connected together along one edge thereof, said inner panel having its free edge connected to said sleeve and said outer panel having its free edge connected to said front and back panels respectively, said last-mentioned connected edges of said front and back bi-swings each connecting with said front and back side seams respectively at a point below the connection between the gusset and the under-arm portion of the sleeve.

50 5. In an article of apparel such as a coat or the like, a front panel and a back panel connected along a shoulder seam and having a sleeve opening therebetween, a side gusset connecting said panels and forming therewith front and back side seams extending from the under-arm portion of the sleeve opening, a sleeve, said sleeve being connected to the front and back panels at the shoulder seam and to said gusset, and a front and back bi-swing extending from the shoulder seam to said front and back side seams respectively and connecting said sleeve to the edge of said sleeve opening in said front and back panels respectively, each of said bi-swings comprising an outer panel and an inner panel connected to-

gether along one edge thereof, said inner panel having its free edge connected to said sleeve and said outer panel having its free edge connected to said front and back panels respectively, said last-mentioned connected edges of said front and back bi-swings each connecting with said front and back side seams respectively at a point below the connection between the gusset and the under-arm portion of the sleeve, said last-mentioned edges of said back bi-swing terminating at said back side seam at a point above the terminating point of the said last-mentioned edges of the front bi-swing with the front side seam.

5. In an article of apparel such as a coat or the like, a front panel and a back panel connected along a shoulder seam and having a sleeve opening therebetween, a side gusset connecting said panels and forming therewith front and back side seams extending from the under-arm portion of the sleeve opening, a sleeve, said sleeve being connected to the front and back panels at the shoulder seam and to said gusset, and a front and back bi-swing extending from the shoulder seam to said front and back side seams respectively and connecting said sleeve to the edge of said sleeve opening in said front and back panels respectively, said rear bi-swing extending to a point beneath the under-arm portion of the sleeve above that of the front bi-swing.

6. In an article of apparel such as a coat or the like, a front panel and a back panel connected along a shoulder seam and having a sleeve opening therebetween, a side gusset connecting said panels and forming therewith front and back side seams extending from the under-arm portion of the sleeve opening, a sleeve, said sleeve being connected to the front and back panels at the shoulder seam and to said gusset, and a front and back bi-swing extending from the shoulder seam to said front and back side seams respectively and connecting said sleeve to the edge of said sleeve opening in said front and back panels re-

spectively, said side gusset and said shoulder seam connection providing only direct connection of the sleeve to the body of the article, all other connection between the sleeve and the body of

- 5 the article being through said front and back bi-swings.
7. In an article of apparel such as a coat or the like, a front panel and a back panel connected along a shoulder seam and having a sleeve opening therebetween, a side gusset connecting said panels and forming therewith front and back side seams extending from the under-arm portion of the sleeve opening, a sleeve, said sleeve being connected to the front and back panels at the shoulder seam and to said gusset, and a front and back bi-swing extending from the shoulder seam to said front and back side seams respectively and connecting said sleeve to the edge of said sleeve opening in said front and back panels respectively, each of said bi-swings comprising an outer panel and an inner panel laid parallel to one another and connected together along one edge thereof, said inner panel having its free edge connected to said sleeve and said outer panel having its free edge connected to the front and back panels respectively.
